Charles R. Delt.
Spattering Patent.

9318X

The Schedule referred to in this Spattering Patent and making
part of the same containing a description in the words of the said
Charles R. Delt. of his improvement in the machine for Plant-
ing Corn - it is all to whom these presents shall come -

Be it known that I Charles R. Delt. residing in the city
of Washington and in the district of Columbia, and State
of Maryland have invented a new and useful improvement
in the machine used for planting corn and that the following
is a full and exact description of the construction and operation
of the said machine as invented or improved by me -

A square frame is to be formed by two side pieces connected
by cross bars, the sizes of which will vary according to the wish
of the builder. A little on each side of the centre of these cross
bars on the top thereof is to be placed ^{each} a cross or another
long bar running parallel with the sides and project-
ing some distance in front of the cross bar. It is intended
that a wheel should pass between them in front of the
frame, and beyond that is applied the point of a draught
harrow which will scour the cross or armpits of these pieces by
battering the side of the long parallel bar, the space is closed by
a broad flat piece resting at each end on the cross bar
beneath it. A similar groove lies on the other space on
the opposite side and in each of them a long sliding bar
slides which very easily falls the groove and may be some
what shorter than the side piece, but will project in front
towards the eye of the wheel having a handle on each end
to which it is moved by means of connecting bars & pins
jointly so that the middle of the slide may be always horizontal
Beneath these slides and grooves is placed a long narrow hinged
shuttle bar for the seed to drop into. It extends across the frame

from side to side, six length. & occupies six width nearly half the space between the cross bar, one side of this box making about a central division between them which with the opposite side is placed perpendicular, having both the ends (sloping) from the side piece of the frame to the nozzle or mouth of the box, where all four unite in a tube through which the seed drops.

This box has a division in the center from one side to the other, nearly touching nearly as low as the mouth tube the side of which will be found very difficult, as it is intended to prevent the seed from rebounding off going out obliquely & consequently, irregularly, in the terrace, & how the manner in which it deposits the seed regularly in this box is by the following contrivance.

Having already said that the length of 18 spans at the sloped ends under the ground, form a small hole through this ground near the back end, sufficient for the seed to pass. & it will consequently drop into the box. & slides down its sloped edge & out at the mouth of the tube again in order to bring the seeds separately or few in number & at intervals to the hole. I make another hole in the sliding bar (which works in this groove) near the back end & so proportioned that the length of the catch arm shall cause it whilst the bar be forced forward to pass over on to the hole in the groove. The seed which lies in a covered hopper & in sufficient quantity for a sowing, about and in contact with the slide, must be passed into this hole & then remain until by the motion of the slide it is thrust on towards the hole in the groove, on arriving at which & the opening being free it drops with the box and out at the tube mouth into the terrace. Which has been previously opened by a shovel or other shaped plough connected with the frame in front of the tube mouth. The seed is covered by bars or other shaped contrifig resembling boomerangs on each side of the tube & secured in the side piece of each side of the frame. The plough shank passes through

through a plate fastened between the long parallel bars underneath and in front of the hoppers shaped bays. It also rises through a block placed above them half way in the seed hopper where at its ^{end} is a nut, and screw to receive it. Beneath the plate a shoulder is made on the back of the shank intended not only to bear against the plate but also to allow of the application of a wedge in order to regulate the depth of ploughing this being thrust in between the shoulder and plate of course driving out the plough blade further into the ground. The block above also slopes to an edge at each side, opposite to a corresponding slope attached to the ends of the bay in order to keep the seed collected as much over the sliding bar as possible. It will be desirable at times such as at sowing &c to stop sowing for this I have the following contrivance. On the top of each side piece of the frame fasten on a broad flat strip to lap a little way over the ground piece & thumb hole it fasten the strip to be about as long as the ground. On the inner under edge where it so laps I form a groove and place another tongue flat strip so wide as to fill up the space between or from this groove and the long parallel bar next to it & to lie immediately on top of the sliding bar which has the hole in it so wide as to prevent seed getting between. These tongue pieces are connected together by a short strip bar laid across the long parallel bars & from this a long tongue or neck leads to the narrow connecting bar between the handles which are fastened to the sides of the frame. There then is placed a pin to fit two holes made in the end of this tongue. when the length of the tongue strip is such as that when the short strip bar is thrust forward as far as the side of the hopper of seed which stops it, then they will cover the hole ^{in the tongue} prevent the escape of the seed. At this point a hole is filled to the pin to retain it there as long as desired.

to cause sawing. The tongue being raised of the frame & the crop bar & strips removed or drawn back uncovering the hole for recommitting. & here another hole in the tongue fits the pin in like manner. To prevent the short crop bar and strips from being withdrawn too far, a stop or check is placed on the back end of each front bar. By this arrangement the advances of the machine deposited the seeds regularly and uniformly upon the surface & also covers it over but in order to render the ground as smooth and fine as desirable. I also attach a harrow to the end of the side pieces of the frame. so as to follow and complete the operation. This harrow frame containing a combination of the stationary or fixed teeth & the revolving cylinder of teeth. the frame being furnished on the front bar with a set of teeth curving forward & behind these revolves a cylinder furnished with smaller straight ones. and attached to the handle bar & from thence to the connecting rod between the handles. It should be harrowed at the time of turning or raising the hand bar. These last are long enough to project behind the harrow so as to allow room for the ploughman to walk and guide this harrow. It also applies to other seeds as feed &c &c. What follows is my invention and not previously known in the above described machine. is First. The manner of producing the motion in the sliding bar by means of the clevis or cam and pivot joint; but not the construction of the sliding bar or hole. Second. the method of closing the holes by means of the tongue flat strips and governed pins of the revolving short crop bar by which to operate them. In testimony that the above are exact description of the construction of my improvement as invented before I have set my hand this third day of October in the year eighteen hundred and thirty five.
